PROCESS FOR THE SEPARATION OF GAS
MIXTURES

Franz Pollitzer, Grosshesseloh, near Munich,
Germany, assignor, by mesne assignments, to
Union Carbide and Carbon Corporation, a
corporation of New York

Application November 4, 1930, Serial No. 493,375
In Germany March 10, 1930

4 Claims. (Cl. 62—175.5)

The processes at present in use for the separation of gas mixtures by cooling to low temperatures presuppose, as is well known, a preliminary removal from the gas mixture of such components as will become separated in a solid state on cooling. If this removal, either by a physical or chemical process, is incomplete, the working period of the apparatus used in the separation is shortened by the solid deposits formed. When separating gaseous products of destructive distillation, such as coke oven gases, there is added to the difficulties caused by separation of water vapor, carbon dioxide and acetylene in the solid state, as a further difficulty the formation of easily decomposable or explosive substances from the condensed hydrocarbons and nitrogen oxides, because these accumulate constantly during operation in the apparatus used for the separation and cause the explosive destruction of the apparatus when it is warmed to normal temperatures.

The present invention avoids entirely these difficulties and renders superfluous the cumbersome and expensive cleaning processes of the gases in the preparation for cooling to low temperature. The cooling of the gases, especially in the range of temperatures in which the above mentioned components are deposited in solid state, is carried out according to the new process by means of periodically interchanged regenerators, through which the compressed gas from the compressor and the cold separation products pass in alternation, while the transfer of the refrigeration from the outgoing to the incoming gases is effected by the regenerator. In passing through the regenerator the easily condensable impurities separate from the incoming gas in solid form, while inversely the cold outgoing gases being free from the impurities are capable of absorbing a certain amount of the impurities on their way through the regenerator and of carrying them out of the same. The impelling force for the re-evaporation of the solid deposits is proportional to the difference between the vapor pressure of the solid deposits at any point of the regenerator and their partial pressure in the gas which passes that point.

In actual practice in the low-temperature separation of gases the conditions are exactly opposite to those required by the above relation, for at every point of the regenerator the temperature during condensation must always be higher than during re-evaporation.

Furthermore re-evaporation is made more difficult by the fact that the amount of gas avail-

able for the re-evaporation is frequently smaller than the amount of fresh gas. This is the case, for example, when one of the products of decomposition is to be obtained separately in pure state. In such a case this product must not be taken out through the regenerator, since it would become contaminated with the impurities previously deposited therein. Hence only a fraction of the amount of gas which passes through the regenerator as fresh gas is available for the re-evaporation.

Now I have discovered a method which insures the complete re-evaporation of the deposited impurities even where only a fraction of the amount introduced as fresh gas is available for the purpose and where there are considerable differences between the temperature of condensation and of re-evaporation. For this purpose I so adjust the pressure of the incoming gas that at every point of the regenerator where condensation takes place the product of the partial pressure of each condensation product and the effective total volume is smaller during the intake period than is the product of the like factors during the outgo period at the same point of the regenerator. The term "effective total volume" is used in the specification and claims to denote the volume of gas passing a given point in the regenerator during a given period of time, for example during one period of regenerator operation. It is determined by correcting the volume of gas passing into or out of the regenerator during the selected period for the temperature and pressure of the selected point in the regenerator. For example, if 100 cubic meters of gas (measured at 0° C. and 735 mm Hg) pass through a given cross-section of the regenerator under a pressure of 5 kg. per sq. cm. and at a temperature of 159° abs., the "effective total volume" of gas at this point in the regenerator is

$$\frac{100 \times 1 \times 159}{5 \times 273} = 11 \text{ cubic meters}$$

In general the pressure of the fresh gas may be made even slightly higher than corresponds to the minimum pressure determined by the above relation in order to have for the re-evaporation a sufficient partial pressure difference between the condensate and the absorbing gas. The condensation of the gas at a higher pressure requires of course a higher expenditure of energy. But this energy can be utilized, for example, when carrying out rectification processes, by letting a rectification under pressure precede a rectification at ordinary pressure, or when separating a

nitrogen-hydrogen mixture from the coke oven gas by low temperature cooling under pressure for the synthesis of ammonia where the produced mixture of nitrogen-hydrogen is needed under pressure. Furthermore it is possible also to take advantage of the increased pressure of the fresh gas in such a way as to cause the separation products released from pressure to pass with great velocity through the regenerators, whereby a saving of heat exchange surfaces and hence of the cost of construction can be effected. The elimination of the preliminary purification of the fresh gas for removing water, carbon dioxide, acetylene and the like impurities, which in the known low temperature process had to be removed prior to low temperature heat exchange, results in a considerable saving in the cost of construction as well as of operation. In the separation of coke oven gas or other combustible gas mixtures at low temperatures the separate treatment of the gas with chemicals at present used especially for the removal of the nitrogen oxide is done away with.

Of course, the treatment must be so conducted that the whole of the fresh gas is freed of its impurities. For this purpose the whole amount of fresh gas must be passed through the regenerator and be cooled. But this is possible only if the entire amount of the decomposition products is made to exchange heat with the fresh gas and passes through the regenerator. Now if one of the separated products is to be obtained in a pure state and a contamination even with very small amounts of foreign matter is to be absolutely avoided, as is the case, for instance, with a mixture of nitrogen-hydrogen produced for the synthesis of ammonia, it becomes necessary to take special measures for the passage of the pure products through the regenerator.

I accomplish this by conducting the pure product through conduits which are in heat-conducting relation with the filling mass of the regenerator so that the gas transmits its heat content to the entering fresh gas by way of the storage mass without becoming contaminated.

The invention is illustrated by way of example by means of the accompanying drawings in which:

Fig. 1 represents a schematic representation in partial section of one embodiment of the invention;

Fig. 2 represents a schematic representation in partial section of another embodiment of the invention; and

Fig. 3 is a schematic representation of a particular application of the invention.

Fig. 1 represents a pair of regenerators 1 and 2, which are adapted for carrying out this process. The regenerators contain filling material 3, as well as bundles of pipe 5, which are in heat-conductive relation with the filling material. The fresh gas passes through the valve 7 into the regenerator 1, deposits its impurities there, and at 13 passes through valve 8 to the separation apparatus not shown in the drawings. Of the separation products, the residual gas enters at 12, passes by way of valve 9 through regenerator 2 which at this time is not traversed by the fresh gas, and leaves said regenerator 2 together with the re-evaporated impurities through valve 7. The product to be obtained separately enters at 14 and is passed out by way of the valve 10 through the bundle of pipes, corresponding to 5, of the regenerator 2, gives off its cold there without absorbing the impurities, and leaves the re-

generator at valve 11 or the product to be obtained separately may be passed in parallel through the pipe bundles of both regenerators. Switching of the gas streams is effected by means of the valves at regular intervals in such a way that the fresh gas alternately passes through the regenerator 2 and the decomposition product through the regenerator 1 and conversely.

Another method is as follows: First, that fraction or those fractions are sent through a regenerator in the cooling period, which may be contaminated by re-evaporation of solid deposits, then after the regenerator has thus been cleaned, that fraction is sent through the regenerator, 15 which is to be obtained in a pure state. Three regenerators are required for carrying out this process in continuous operation, the tubes 5 being unnecessary.

In Fig. 2 there is schematically represented a 20 group of regenerators 1, 2 and 3, with the switching valves 4, 5, for the fresh gas, 6, 7, for the residual gas, and 8, 9, for the product which is to be obtained separately. With the switching valves in the position shown the fresh gas passes 25 through the regenerator 1, the residual gas from the separation apparatus enters at 12 and by way of valve 6 passes to the regenerator 2, and the other product to be obtained separately enters at 14 and is carried by way of the valve 8 30 through the regenerator 3. During this period of operation the impurities coming from the fresh gas are deposited in the regenerator 1, in regenerator 2 they are re-evaporated and carried out, and the separately obtained gas which must not 35 absorb any impurities passes through the third regenerator which during the preceding operative period was freed of impurities. In the succeeding period of operation the fresh gas coming from 10 passes through 3, the residual gas coming 40 from 12 passes through the regenerator 1, and the product coming from 14, which is to be obtained separately, passes through the regenerator 2 which had been cleaned in the preceding 45 period of operation. In the third period the fresh gas passes through 2, the residual gas cleans the regenerator 3, and the third gas passes through the regenerator 1.

The process will be described for purposes of illustration by a definite example, namely by the separation of carbon monoxide from illuminating gas, with reference to Fig. 3.

The solution of this important problem has seemed hitherto economically impossible with the means at the disposal of the low temperature technician. Only by the elimination of the expensive preparatory cleaning of the gas and by the substantial reduction of the cost of the apparatus by employing regenerators for cooling the gas has an economically useful solution of 55 the problem been obtained.

Illuminating gas which has been compressed to a pressure of 5 to 10 atmospheres, without a preparatory purification for the removal of carbon dioxide, water vapor or other impurities (except tar and sulphur) enters at 1 and passes through the regenerator 2, which is filled, for example, with massive, tightly packed strips of sheet iron having a large area. Previous to this the regenerator has been cooled down so much that during an operation period which may last from 1 to 3 minutes the gas leaves at nearly the temperature which prevails at the lowest point of the regenerator. During the passage of the fresh gas its impurities such as water or carbon 75

dioxide are deposited in solid form as snow together with films of liquid condensates. The fresh gas freed from its impurities now reaches, by way of the valve, the bundle of tubes of the counter-current heat exchanger 6, in which the rising gas current is cooled, with rectification effect, to such an extent that the main part of the methane is separated at 7. The liquid methane is expanded through the valve 8 into the space 10 of the counter current heat-exchanger 6 surrounding the bundle of tubes. The gaseous residue of the fresh gas passes into the tube bundle of the counter current heat-exchanger 9, in which bundle the main portion of the carbon monoxide 15 is liquefied. The liquid carbon monoxide separated at 10 is expanded through valve 11 and serves for cooling counter current heat-exchangers 9 and 6. The remainder of the gas which has not been liquefied and is composed mostly 20 of hydrogen is reheated in the counter current collector 9 and at 12 enters the expansion engine 13, in which it cools down doing work and furnishes at the same time the amount of cold required for the process. The cold expanded 25 gases are returned at 14 to the counter current heat-exchanger, at 15 they pass, together with the liquid methane expanded through valve 8, into the counter current exchanger 6 and finally 30 return by way of switch valve through the conduit 16 into the regenerator 3 where they re-evaporate the solid and liquid deposits. At 18 the gas charged with impurities is carried off. The fraction 17 of the carbon monoxide obtained 35 separately passes by way of the pipe bundle 4 through the regenerator 3 and transmits its cold to the regenerator mass. After the lapse of a definite period the direction of the gas currents is changed in such a way that the fresh gas passes through the regenerator 3, the cold gases 40 pass through the regenerator 2, which in consequence of absorption of heat from the fresh gas have become somewhat warmed up, and so on with regular uniform alternation. The method of operation with three regenerators shown by 45 Fig. 2 may also be employed for the removal of carbon monoxide.

If the gas mixtures to be cooled contain very easily condensable constituents, such as benzol hydrocarbons, it is advantageous to remove these substances by connecting ahead of the regenerators apparatus for cooling the gas down to about minus 50° C. The cooling in this first step is carried out by counter current heat exchange, and not until after the separation of the benzol is the 50 regenerator cooling employed. The solid benzol deposited in the cooler can be melted and drawn off by heating the cooler after a more or less extended period of operation.

I claim:—

60 1. A process for the separation of gaseous mixtures into components, which comprises cooling an inflowing gas mixture by contact with a

cold regenerative body, separating the cooled mixture into higher and lower boiling components and cooling another regenerative body by passing separated higher and lower boiling components in contact therewith in succession.

5

2. A process for the separation of gaseous mixtures into components, which comprises cooling an inflowing gas mixture by contact with a cold regenerative body, separating said gas mixture into higher and lower boiling components, cooling 10 a second regenerative body by contact with a separated component, cooling a third regenerative body by contact with another separated component, periodically alternating the flow of incoming gas and outgoing higher and lower boiling 15 components with respect to a given regenerative body, and contacting the ingoing gas and outgoing higher and lower boiling components with a given regenerative body in cyclic succession.

3. A process for the separation of gas mixtures 20 into components, which comprises separating a gas mixture into higher and lower boiling components at a low temperature, passing separated higher and lower boiling components in heat exchange contact relation to the surface of a regenerative body in cyclic succession to transfer their cold to such body, and then passing a subsequent charge of the gas mixture in continuation of the cyclic succession in heat exchange contact relation with the same surface of said body whereby 25 said gas mixture is chilled.

4. A method of separating gas mixtures containing nitrogen, carbon monoxide, and methane, which comprises compressing said gas mixture, conducting the mixture first through cold regenerators to effect the condensation of impurities contained therein, then through a plurality of countercurrent rectifying devices to separate fractions of intermediate boiling point leaving an uncondensed remainder, expanding said remainder with production of external work to cool the same, passing the expanded and cooled remainder in heat exchanging relation with a portion of the incoming gas mixture, conducting separated components through cold regenerators simultaneously 40 with the residual gas and in heat exchanging relation therewith, and periodically reversing the flow of the incoming gas mixture and of the outgoing residues through said regenerators to evaporate the impurities condensed therein, the cycle 45 of gas flow being so arranged that the period of flow of the incoming gas mixture through a regenerator is followed by a period of flow of a separation product such as will not be detrimentally affected by the evaporation thereinto of 50 the condensates to be evaporated, whereby the regenerator is placed in the desired condition to conduct the pure separation product therethrough without contamination of the same, and passing the said purified product through said regenerator 55 for transferring refrigeration thereto.

FRANZ POLLITZER.
